FISHING REEL

Marvin T. Shumate, 2316 Liverpool, Mesquite, Tex.
75149, and Bobby G. Williams, 9551 Crestshire, Dallas,
Tex. 75217

Filed Oct. 22, 1971, Ser. No. 191,973

Term of patent 7 years

Int. Cl. D22—05

U.S. Cl. D22—25

FIG. 1

FIG. 2

FIG. 3

FIG. 4

FIG. 5

FIG. 6

FIG. 7

FIG. 8

FIG. 1 is a perspective view of a fishing reel embodying the invention, with the component parts thereof shown separately;

FIG. 2 is a similar perspective view of the reel shown in FIG. 1, the view taken from the opposite sides;

FIG. 3 is a view similar to FIG. 1, with the component parts assembled into the reel;

FIG. 4 is a perspective view similar to FIG. 2, with the component parts assembled in the reel;

FIG. 5 is a perspective view of a modified embodiment of the invention;

FIG. 6 is an elevational view of the reel shown in FIG. 5;

FIG. 7 is a perspective view of another embodiment of this invention; and

FIG. 8 is an elevational view of the reel shown in FIG. 7.

In FIGS. 5-8, the radial lines on the knob-like portions of the reels are fluting.

We claim:

The ornamental design for a fishing reel, as shown and described.
